UNITED STATES PATENT OFFICE.

HARRY RANDOLPH VAN DEVENTER, OF SUMTER, SOUTH CAROLINA, ASSIGNOR TO SPLITDORF ELECTRICAL COMPANY, OF NEWARK, NEW JERSEY, A CORPORATION OF NEW JERSEY.

IGNITION DEVICE FOR INTERNAL-COMBUSTION ENGINES.

1,492,887.

Specification of Letters Patent.

Patented Jan. 3, 1922.

Application filed October 13, 1917. Serial No. 196,373.

To all whom it may concern:

Be it known that I, HARRY RANDOLPH VAN DEVENTER, a citizen of the United States, residing at Sumter, in the county of 5 Sumter and State of South Carolina, have invented certain new and useful Improvements in Ignition Devices for Internal-Combustion Engines, of which the following is a specification, reference being had 10 to the accompanying drawing.

The invention relates to new and useful improvements in ignition devices and more particularly to an ignition device having a fixed and a movable electrode to which current is supplied by a magneto generator.

An object of the invention is to provide an ignition device of the above character which includes independent supporting brackets, one of which carries the electrodes 20 and the other the magneto generator, and to provide means for positioning said brackets relative to each other so as to maintain proper synchronism in the movements of the current generating member of the magneto generator and the movable electrode, and also so as to ensure proper synchronism 25 between these parts when the brackets are replaced after having been removed for any purpose.

30 In the drawings,—

Fig. 1 is a side view of the ignition device with the generator in place;

Fig. 2 is a front view of the ignition device, the generator being removed to show 35 the actuating mechanism;

Fig. 3 is a top plan view of the two parts of the bracket assembled.

The invention consists broadly in the supporting means for the electrodes and the 40 movable generator. In the present embodiment of the invention, I have provided two supporting brackets which are independent of each other in the sense that when the brackets are removed from the engine they 45 are disconnected. On one of these brackets is mounted the electrodes, and one of the electrodes is preferably movable relative to the other for producing the spark. On the other bracket is mounted the magneto generator and also preferably the actuating 50 springs therefor. The two brackets are provided with interengaging parts which serve to position one bracket relative to the other, so that when the brackets are attached to

the engine cylinder they will be held in 55 fixed relation to each other by these interengaging parts co-operating with the means which secures the brackets to the engine cylinder. This prevents either bracket from becoming loose on its supporting means and 60 shifting so as to throw the current generating member and the movable electrodes out of synchronism.

It is understood, of course, that in this type of ignition device the time interval 65 at which the current rises to a maximum peak is very short and in order to produce an efficient spark, the movable electrode must be moved to separate the electrodes for producing the spark within this short 70 interval of time when the current generated by the magneto is at a maximum. After the parts have been properly adjusted, so as to bring about a synchronism in the movements of the current generating member 75 and the movable electrode to secure maximum spark, these interengaging parts between the brackets will prevent any shifting of one bracket relative to the other, and, therefore, maintain the synchronism 80 and the maximum spark.

Furthermore, the brackets at times must be removed to permit the cleaning of the electrodes and when they are replaced the interengaging parts ensure that the brackets 85 shall be put back in exactly the same relation to each other as they were when the parts were adjusted for a maximum spark, and, therefore, said brackets may be removed and replaced without disturbing the 90 synchronism of the moving parts referred to and without disturbing this maximum current generation and the spark produced thereby.

The invention will be better understood 95 by a brief reference to the drawings in detail wherein my improved ignition device is shown as embodying two supporting brackets indicated at 1 and 2 in the drawings. The bracket 2 is provided with a 100 sleeve 3, which projects into an opening in the cylinder wall and mounted in this sleeve is a fixed electrode 4 and a movable electrode 5. Said electrodes are provided with the usual ignition points 6 and 7 respectively, which are normally in contact and which are separated for the purpose of 105 producing the ignition spark. The movable

electrode is provided with an arm 8 at its outer end. A spring 9 bearing at one end against the said arm and at its other end against an abutment 10, serves to hold the ignition points in contact. The bracket 2 is clamped to the cylinder wall by a stud bolt 11, on which is the usual threaded nut 12^a.

The bracket 1 is located at one side of the bracket 2 and as a means for positioning said brackets relative to each other and holding them in this predetermined position, I have provided interengaging fitted parts. The adjacent faces 12 and 13 of the brackets are milled so as to fit snugly together. The bracket part 1 is provided with recesses 14 adapted to receive lugs 15 carried by the bracket 2. These lugs and recesses form the interengaging parts referred to above and serve as a means together with the milled faces 12 and 13 for exactly positioning one bracket relative to the other and holding said brackets in this predetermined position. The bracket 1 is held against the cylinder wall by stud bolts 16 and 17, on which are threaded nuts 18.

From the above, it will be readily seen that the two brackets may be readily removed from the engine for the purpose of cleaning the electrodes and when so removed the two brackets are entirely separate from each other and the bracket 2 carrying the electrodes may be completely immersed in gasoline or the like for cleaning the electrodes. After the electrodes have been cleaned, the brackets may be again placed on the engine cylinder and these interengaging parts will exactly re-position the brackets, just as they were before removal from the engine, so that when once the parts are in proper synchronism, that is, the movable electrode is operated just at the right time interval to correspond to the maximum current generation, this synchronism of the parts will always be maintained.

Furthermore, by these interengaging parts the two brackets may be assembled when detached from the engine and they will position said brackets in exactly the position they will have on the engine and they may be held in this position by hand and the generator operated to see whether or not proper spark is produced, and this operation of the generator and the movable electrode will be under as near normal conditions as can be obtained.

The bracket 1 is provided with a shelf 19 on which is mounted the magneto generator G. Bolts 20 pass up through the shelf and are threaded into the base of the generator. On the shelf carrying the generator is an upwardly extending standard 21. The trip lever 22 is supported by a shaft fixed to the standard 21. Said trip lever is provided 65 with a cam projection 22^a adapted to strike

the arm 8 of the movable electrode for separating the ignition points. The tip lever is provided with pins 23 and 24. A spring 25 engages a roller on the pin 23 and also a roller on the pin 24 carried by an overhanging arm 25^a mounted on the supporting bracket 1. A spring 26 engages a roller on the pin 24 and also a roller on the pin 27, carried by a lug 28 on the shelf 19 and extending downwardly therefrom.

A push finger 29 is adapted to engage the shoulder on the trip lever and move the same to a predetermined point where it is released, so that the springs may return the trip lever, causing the same to actuate the movable electrode, and also the armature or current-generating member of the magneto generator. A generator armature is provided with a forked arm 30, adapted to engage the pin 24, so that the movements of the trip lever are imparted to the armature shaft.

While I have described in detail one particular form of magneto generator and means for operating the armature, it will be understood that these parts may be greatly varied, as the essential feature of the invention consists in the two supporting brackets, one of which carries the electrodes and the other of which carries the magneto generator, which brackets when detached from the engine cylinder are entirely separate from each other, so that the bracket carrying the movable electrodes may be immersed in gasoline or the like for cleaning, as above noted, and when the parts are re-assembled, the interengaging features of the brackets bring about the same position of the brackets relative to each other as before they were removed from the engine cylinder thus ensuring that the movements of the armature and the movements of the movable electrode, will always be in proper synchronism after once these parts have been adjusted. These interengaging parts also, as above noted, maintain this position of the brackets, even though the bolt holes through which the bolts pass for securing the brackets to the engine cylinder wear so that the brackets might otherwise shift on the bolts. If there is any shifting of one bracket, it will be imparted likewise to the other, so that both brackets will, as stated, be properly held in fixed relation to each other.

While I have shown separate means for securing the brackets to the engine cylinder, it is understood, of course, that the construction of the brackets and the arrangement of the brackets relative to each other and the securing means therefor, may be greatly modified so long as the means for maintaining the position of the brackets relative to each other is utilized, as this is the broad feature of my invention.

Having thus described my invention,

what I claim as new and desire to secure by Letters Patent, is:—

1. An ignition device including in combination, a supporting bracket, a fixed and a movable electrode carried thereby, a second supporting bracket, a magneto generator mounted on said second bracket, a trip lever and actuating springs for oscillating the armature of the generator carried by said second bracket, means for securing said brackets to the engine cylinder, and means for holding the brackets in a fixed position relative to each other. 10
2. An ignition device including in combination, a supporting bracket, fixed and movable electrodes carried thereby, a second supporting bracket, means for securing said

brackets to the engine cylinder, means for holding the brackets in fixed position relative to each other, said second supporting bracket having a supporting shelf for a magneto generator, a magneto generator carried thereby, a standard carried by said shelf, a trip lever supported by said standard and adapted to oscillate said armature, a lug carried by said shelf, an overhanging arm carried by said second bracket, and springs connected respectively to the trip lever and to the lug and overhanging arm for actuating the trip lever. 20 25 30

In testimony whereof I hereunto affix my signature.

HARRY RANDOLPH VAN DEVENTER.
